UNITED STATES PATENT OFFICE.

JOHN S. WORTH, OF COATESVILLE, PENNSYLVANIA, ASSIGNOR TO JOHN S. WORTH AND WILLIAM P. WORTH, OF COATESVILLE, PENNSYLVANIA.

DUMPING-CAR.

1,133,248.

Specification of Letters Patent. Patented Mar. 23, 1915.

Application filed October 1, 1914. Serial No. 834,494.

To all whom it may concern:

Be it known that I, JOHN S. WORTH, a citizen of the United States, and a resident of Coatesville, county of Chester, State of Pennsylvania, have invented certain Improvements in Dumping-Cars, of which the following is a specification.

My invention relates to certain improvements in dumping cars, particularly cars used for dumping ores and like material, and it is especially adapted for use in connection with iron and steel works, where material is to be quickly discharged.

One object of the invention is to construct a car of this type so that the material can be dumped from one end of the car; the car carrying its own mechanism by which the body is raised to such an angle as to be discharged by gravity.

20 A further object of the invention is to mount the draw bar with the coupling on the tilting body of the car.

In the accompanying drawing:—Figure 1, is a side view of my improved dumping car; and Fig. 2, is a plan view of the same.

Referring to the drawing, 1 is the main framework of the car supported on trucks 2 of the usual type, and at the forward end of this frame is a draw bar and coupling 3 by which the car can be coupled to another car, if desired. The trucks are supplied with the usual brake mechanism and this brake mechanism is controlled from the hand wheel 4 at the forward end of the car.

5 is the body of the car having a base frame 6 and vertical braces 7 which stiffen the sides of the body portion.

8 is the pivot on which the body portion 40 swings on the main frame 1. The body portion has a downwardly extending member 9 to which the hoisting chain is attached, so that when the body portion is turned on its pivot, it can be turned to the proper incline 45 without making a cumbersome mast.

10 is the mast mounted on the main frame 1, and this mast is deflected at an angle rearwardly toward the body portion 5. The body portion is turned on its pivot by hoisting mechanism connected to a locomotive, and on the frame of the mast 10 is a drum 11 mounted on a shaft 12. A rope 13 leads from this drum and is attached to the locomotive after it has been uncoupled from the car, and the car can be locked by the brakes

or blocks, as desired, and as the locomotive moves away from the car it will uncoil the rope and will cause the drum 11 and its shaft 12 to turn. The shaft is geared through a pinion 14 and gear wheel 15 to an intermediate shaft 16 which, in turn, is geared through a pinion 17 and a large gear wheel 18 to the main drum shaft 19 on which are the drums 20 having chains 21, as shown by dotted lines, Fig. 1, which are 35 coiled as the body portion 5 is elevated.

At the outer end of the mast 10 are four rope or chain sheaves 22 and the drum 20 is grooved to receive the four ropes 21 which pass around these sheaves and are attached 70 to the drum. The opposite ends of the ropes extend down to the front of the body portion 5 and are attached to an angle bar 23 on each side of the extension 9 of the body portion 5. The ropes or chains preferably pass around guide wheels 24 at the corner of the extension. When tension is applied to the rope 13 by the movement of the locomotive, motion is imparted through the train of gearing to the drum 20 and the 80 drum slowly coils the rope or chain 21, causing the body portion 5 to be turned on its pivot 8 until it is at the proper angle to discharge its load. As soon as the load is discharged, the engine can be reversed and 85 moved toward the car and the weight of the body portion will cause the drum 20 to unwind and the drum 11 to wind the rope 13 thereon.

It will be noticed that the coupling 25 and 90 the draw bar at the rear of the car is carried by the pivoted body portion. By this construction, I am enabled to open the entire width of the car at the end and to arrange the pivot some distance from the end. 95 When the material is dumped it will clear the coupling.

The forward end of the body portion is closed and the rear end has a door 26 hung from a pivot 27 at the upper rear end of 100 said body portion.

28 is a latch, which engages the bottom of the door and holds it closed when the body is in the normal position, as illustrated in full lines, Fig. 1. This latch has an arm 105 29, which extends over a bar 30 secured to the fixed framework 1 of the car and this bar arm is so shaped that when the body portion is elevated the latch will be moved away from the door so that it will swing 110

free and will allow the load to be discharged. As soon as the body portion assumes its normal position, the latch automatically engages the door.

5 The operation is as follows:—The car, with the load thereon, is moved to the position where it is desired to dump the load and the locomotive is uncoupled from the car and the rope 13 is attached to the locomotive, or, if there is a hoisting engine located at a fixed point, it can be used instead of the locomotive if desired. The brakes are applied to the wheels of the car and blocks are preferably used to hold the car in a fixed position relative to the dumping point. As tension is applied to the rope 13 it causes the main rope drum 20 to rotate and this motion is imparted to the free end of the car body and, as the ropes or chains 21 are coiled on the drum, the body is turned on its pivot 8 to such an angle that the load will slide from the body portion and will be discharged from the point desired. As soon as the load is discharged, 25 the slack is released, the weight of the body portion causing the drum 20 to reverse its movement and pay out the ropes or chains 21 and to coil the rope 13 on its drum, after which the car can be moved to receive another load. In some instances, a band or other suitable brake may be applied to a drum on the shaft 11 and this brake 31 may be connected to an operating lever 32 by a rod 33, so that a man standing on the body 30 of the car at the mast can regulate the speed of rotation of the drum 11, if found necessary.

I claim:—

1. The combination in a dumping car, of 40 a main frame; wheels on which the frame is mounted; a body portion pivoted at one end of the main frame; a mast mounted on the opposite end of the car from the pivot; a drum; a hoisting chain or rope passing from 45 one end of the body portion to the drum; and a second drum carried on the first mentioned frame and having a rope thereon to which motion can be imparted by mechanism independent of the car, so as to raise 50 the body portion to the dumping position.

2. The combination of a car having trucks; a main frame supported on the

trucks; a body portion pivoted to the main frame at one end, said body portion being shorter than the main frame; a mast located at the opposite end of the main frame and overhanging the end of the body portion; a drum; a sheave at the upper end of the mast; a chain or rope attached to the bottom of the body portion and extending over the sheave and to the drum; a second drum geared to the first mentioned drum; and a rope mounted on the said second drum and arranged to have motion imparted to it independently of the car so that, when tension is applied to said rope, the body portion will be turned on its pivot and its contents dumped. 55

3. The combination in a dumping car, of trucks; a main frame mounted on the trucks; a body portion pivoted to the main frame at one end and having an extension at the opposite end projecting below the main frame; a mast secured to the main frame in advance of the body portion and extending rearwardly over the body portion; a sheave carried by the body portion; a rope or chain passing from the extension of the body portion up and around the sheave; a drum to which the rope or chain 80 is attached; a second drum geared to the first mentioned drum; and a rope leading from said second drum to any means for imparting motion to the rope so as to cause the main drum to turn and to lift the free 85 end of the body portion to such an incline as will discharge its load. 75

4. The combination in a car, of a main frame; wheels supporting the main frame; a coupling secured to one end of the main 90 frame; a pivot at the opposite end of the main frame; a body portion connected to the main frame by said pivot; a coupling attached to the rear of the body portion; and means for tilting the body portion to 95 the dumping position, the rear coupling moving with said body portion.

In testimony whereof, I have signed my name to this specification, in the presence of two subscribing witnesses.
